LAND

METHOD OF CLEARING FIBERS OUT OF A VESSEL

Application filed December 7, 1929, Serial No. 412,544, and in Germany December 15, 1928.

In the treatment under pressure of cotton fibers with hot liquids it has been found that there are difficulties in clearing out the vessel in which the fibers are treated. The 5 cotton fibers and more particularly the long fibers have the tendency to form into lumps and to felt, when the treating liquid is run off. If the treating liquid should be drawn off by suction, a solid cake of fibrous material 10 is formed, which cannot readily be loosened up again with fresh liquid. Hitherto it has been necessary to clear such fibrous material out of the vessel by hand. It has already been proposed to remove short-fibered fibrous materials, for instance cellulose after 15 it has been boiled together with the lye out of the boiling vessel through the action of compressed air. This treatment, however, entails difficulties when the treating liquid is let off 20 after the boiling operation and in the case of long-fibered fibrous materials, more particularly cotton, it is almost impossible to carry out, as the cotton covered with fresh water does not distribute itself uniformly 25 owing to having become felted, so that when being run off thick lumps of felted cotton get into the outlet pipe or are forced into the orifice of the same, thus blocking up the entire outlet. 30 The disadvantages described above are overcome by the method according to the present invention. The method consists in this, that the cotton fibers in the form of pulp are agitated by means of compressed air and 35 kept in a divided state, the pulp being forced in this state out of the vessel through a pipe extending down into it. When the used treating liquid has been temporarily removed by suction and a firm cake of fibrous material is 40 left, the latter is covered with fresh liquid and thereupon loosened up and agitated with air only. This is preferably effected while the pressure vessel is open so that the contents of the vessel will not be forced into the outlet 45 pipe before they have been thoroughly stirred up.

The new method has the further advantage that it enables the cotton fibers to be forced in a simple manner to considerable heights. In 50 this way it is possible to place the heavy pres-

sure vessels on the ground level, while the other treating apparatus for the cotton fibers are placed aloft.

In the accompanying drawing a diagrammatic view of an apparatus is shown by way 55 of example, in which the method can be carried out.

In the pressure vessel 1 is a pulp of cotton in a liquid 2. Through the pipe 3 which terminates in a perforated coil at the bottom 60 of the vessel, compressed air is introduced. At the commencement of the agitating operation the compressed air can be allowed to escape through the cock 5 until the fibrous material has been thoroughly stirred and distributed. The cock 5 is thereupon closed and the cock 6 in the pipe 4 of large diameter, which extends downwards into the vessel, is 65 opened. Under the action of the compressed air the pulp of fibrous material will rise in 70 the pipe 4. In this way the vessel 1 will be emptied of material all but a small residue. At the bottom of the vessel 1 is a cock 7 which serves the purpose of running off the liquid and which, if a sieve be placed in front of it, can also be used for withdrawing the treating liquid by suction. At the top of the vessel 75 is an opening 8 for charging the vessel.

What I claim is:

1. A method of clearing cotton fibers out 80 of a closed vessel in which they have been subjected to the action of a treating liquid, consisting in running off the treating liquid, letting in fresh liquid, admitting compressed air into the fresh liquid and causing it to 85 agitate the liquid containing the fibers until the latter are evenly distributed throughout the liquid, allowing the compressed air to accumulate in the vessel and thereupon causing it to force the liquid with the fibers out 90 of the vessel through a pipe immersed in the liquid.

2. A method of clearing cotton fibers out 95 of a closed vessel in which they have been subjected to the action of a treating liquid, consisting in running off the treating liquid, letting in fresh liquid, admitting compressed gaseous medium into the fresh liquid and causing it to agitate the liquid containing the fibers until the latter are evenly distributed 100

throughout the liquid, allowing the compressed gaseous medium to accumulate in the vessel and thereupon causing it to force the liquid with the fibers out of the vessel through a pipe immersed in the liquid.

- 5 3. A method of clearing cotton fibers out of a closed vessel in which they have been subjected to the action of a treating liquid, consisting in running off the treating liquid, letting in fresh water, admitting compressed
- 10 gaseous medium into the fresh water and causing it to agitate the water containing the fibers until the latter are evenly distributed throughout the liquid, allowing the compressed gaseous medium to accumulate in the
- 15 vessel and thereupon causing it to force the liquid with the fibers out of the vessel through a pipe immersed in the liquid.
4. A method for clearing fibers out of a vessel comprising admitting liquid to the vessel, agitating the liquid with a compressed gaseous medium to distribute the fibers throughout the liquid, and allowing the compressed gaseous medium to accumulate in the vessel and force the liquid with the fibers out
- 20 of the vessel through an outlet below the surface of the liquid.
5. A method for clearing fibers out of a vessel comprising admitting liquid to the vessel, agitating the liquid to distribute the
- 25 fibers throughout the liquid, admitting a compressed gaseous medium and allowing the compressed gaseous medium to accumulate in the vessel and force the liquid with the fibers out of the vessel through an outlet below the surface of the liquid.

In testimony whereof I affix my signature.
WALDEMAR zur LÖWEN.
